UNITED STATES PATENT OFFICE.

ELIHU THOMSON, OF LYNN, MASSACHUSETTS, ASSIGNOR TO THE THOMSON-HOUSTON ELECTRIC COMPANY, OF CONNECTICUT.

AUTOMATIC CUT-OUT FOR ELECTRIC APPARATUS.

SPECIFICATION forming part of Letters Patent No. 307,818, dated November 11, 1884.

Application filed April 12, 1884. (No model.)

To all whom it may concern:

Be it known that I, ELIHU THOMSON, a citizen of the United States, and a resident of Lynn, in the county of Essex and State of Massachusetts, have invented certain new and useful Improvements in Automatic Cut-Outs for Electric Apparatus, of which the following is a specification.

My invention relates to means for forming a safety or branch circuit around an electric lamp—such, for instance, as an arc lamp—or other electric apparatus in case the continuity of the circuit therethrough be threatened by a break of the connections in said lamp, or by the occurrence of an abnormally-high resistance in some portion of the lamp-circuit.

My invention is intended, primarily, for application to electric-arc lamps, and is herein shown as arranged to work upon the occurrence of an abnormally-high resistance at the arc between the electrodes.

The invention consists in effecting an automatic cutting out or short-circuiting of the lamp by the agency (direct or indirect) of an electric current caused to pass through a vacuous space between two electrodes, contacts, or sets of contact-points, connected, respectively, to opposite sides of the lamp or the electrodes therefor, when the circuit through the lamp or electrodes becomes broken or its resistance becomes abnormally high, so that current will be forced to leap across the vacuous space between the points.

Some of the ways in which my invention may be carried into practice are shown in the accompanying drawings, in which Figure 1 illustrates, diagrammatically, an arrangement of circuits or apparatus for the purpose. Figs. 2, 3, and 4 show modified forms of the electrodes to be used in the vacuous space. Fig. 5 shows an arrangement the equivalent of that shown in Fig. 1.

G, Fig. 1, indicates a globe or receptacle of any suitable kind, into which are introduced wires carrying electrodes, points, or metallic projections placed very near together—say one-fiftieth of an inch or less. The globe G is exhausted to a vacuum of nearly or quite the maximum conductivity and then finally sealed. The vacuum can be produced by any ordinary good air-pump. The wires are connected, re-

spectively, to the two wires leading to the carbons of an electric-arc-lamp, respectively. The connection to one of the carbons is made through a switching-magnet, F, and a contact 55 closed by the action of the latter, as shown. The wire X to the other carbon branches to G, to the rod R, and to the armature or upper contact at K, the closure of which contact by magnet F shunts the arc E and retains F in 60 circuit to hold the contact K closed. When magnet F is not energized, the contact K is held open by a spring, S.

Figs. 2, 3, and 4 show modifications of the points or plates in G, and will explain themselves. A magnet, M, may be used near the arc E, to assist in displacing it, and so establish a large difference of potential of the carbons, even though a short space only exist between them.

The operation is as follows: A long arc at E, from failure to feed, finally results in the establishment of such a difference of potential that a leak occurs through the vacuous space in G, thus energizing the magnet F, and shunting 75 the arc and also G at K, after which the carbons at E remain cut out. Should contact again be formed at E, the magnet F is shunted thereby, and releases its armature and opens the contacts at K.

I do not limit myself to any particular device for effecting the closure of the shunt or safety circuit by the agency of the current forced across the vacuous space by an abnormal increase of potential at the sealed electrodes, as my invention consists, essentially, in combining such sealed electrodes with the lamp or other apparatus in such way as to cause a current to flow from one to the other by an increase of resistance in the lamp, which 85 current is used as the effective or exciting agent in causing a closure of the safety branch to be made.

Instead of an electro-magnet, F, responsive to the current flowing in the vacuous chamber, 95 I may use other devices—as, for instance, a resistance-wire, to be heated by the current flowing. One way of utilizing the heat developed by such current is shown in Fig. 5, where f indicates a fusible wire in the circuit to the electrodes in G and W, a spring-actuated switch controlling the contacts K, and normally held

open by the wire *f*, attached to the switch and to a fixed support. The fusion or breakage of the wire *f* by the current made to flow across the vacuous space between the electrodes in *G* 5 in the way described frees the switch, and the contacts *K* are thereupon closed by the spring acting on the lever *W*.

The construction of the switch-contacts, the form of the globe, method of sealing the same, 10 and shape of electrodes therein may be indefinitely varied without departing from the spirit of my invention.

I am aware that it is well known that a current of electricity of proper potential will leap 15 across the space between two electrodes normally out of contact, and that the current will more readily jump the space if a vacuum of the proper degree be formed between the electrodes.

20 My invention consists, however, not in the device mentioned *per se*, but in the arrangement thereof with relation to the electric lamp or other apparatus whereby a shunting of the latter may be automatically effected under ab- 25 normal conditions of resistance.

What I claim as my invention is—

1. In combination with an electric lamp or other electric apparatus, a short-circuiting or

shunting appliance consisting, essentially, of electrodes placed very near one another, and 30 connected, respectively, to opposite sides of the lamp, and switch devices controlled by the current leaping from one electrode to the other to switch or shunt the lamp.

2. In combination with an electric lamp or 35 other electric apparatus, a circuit-changer or shunting-switch, and an electro-responsive device controlling the same, placed in a circuit in which current may flow by being forced from terminal to terminal through a small partially-vacuous space, as and for the purpose 40 described.

3. The combination, with an electric-arc lamp or other electric apparatus in a circuit, 45 of a vacuous receptacle for opposed electrodes, connected to opposite sides of that portion of the apparatus wherein an abnormally-high resistance may occur, as and for the purpose described.

Signed at Lynn, in the county of Essex and 50 State of Massachusetts, this 7th day of April, A. D. 1884.

ELIHU THOMSON.
